[57] CLAIM

The ornamental design for a watchman data downloader, as shown and described.

DESCRIPTION

FIG. 1 is a perspective view of a watchman data downloader, showing my new design;

FIG. 2 is a front elevational view thereof;

FIG. 3 is a top plan view thereof;

FIG. 4 is a right side elevational view thereof;

FIG. 5 is a back elevational view thereof;

FIG. 6 is a bottom plan view thereof;

FIG. 7 is a left side elevational view thereof;

FIG. 8 is a perspective view of a second embodiment thereof;

FIG. 9 is a front elevational view thereof; and,

FIG. 10 is a top plan view thereof.

The undisclosed views of the second embodiment are identical to those of the first embodiment.
